UNITED STATES PATENT OFFICE.

ERNEST J. ROLLINGS, OF PHILADELPHIA, PENNSYLVANIA.

BORING-MACHINE.

1,230,034.

Specification of Letters Patent. Patented June 12, 1917.

Application filed October 31, 1916. Serial No. 128,740.

To all whom it may concern:

Be it known that I, ERNEST J. ROLLINGS, a subject of the King of Great Britain and Ireland and the Isle of Man, and a resident 5 of Philadelphia, county of Philadelphia, State of Pennsylvania, have invented certain Improvements in Boring-Machines, of which the following is a specification.

My invention relates to certain improvements in boring machines of the type in which the work is carried by rotating chucks and the tool is carried by a bar which projects from a driving head so that the bar can enter the work and the tool will make 15 the cut inside the work.

One object of the invention is to design a boring machine of the above mentioned type so that two or more tool chucks can operate at the same time.

Another object of the invention is to provide means for automatically projecting and retracting the tool on each chuck.

A further object of the invention is to design the boring bar so that a long hole of 25 comparatively small diameter can be bored, the bar having sufficient strength to resist the strains to which it is subjected when the tools are in action.

A still further object of the invention is 30 to provide means for rigidly supporting the boring bar and another object of the invention is to construct the chucks which hold the work so that the work can be rotated positively.

Still another object of the invention is to provide means for adjusting the cam bar to control the movement of the cutting tool so 35 that it can be moved while the tool carriage is stationary in order to project the tool toward the work to cut abrupt angled shoulders.

The invention also relates to certain details which will be fully described hereinafter, reference being had to the accompanying drawings, in which:

Figure 1, is a plan view of my improved boring machine;

Fig. 2, is a side view;

Fig. 3, is a transverse sectional view on 50 the line 3—3, Fig. 1;

Fig. 4, is an enlarged transverse sectional view on the line 4—4, Fig. 1;

Fig. 5, is a transverse sectional view on 55 the line 5—5, Fig. 6;

Fig. 6, is a section on the line 6—6, Fig. 5,

showing the boring bar and tool carrier in outside view;

Fig. 7, is a sectional plan view on the line 7—7, Fig. 5;

Fig. 8, is a sectional view on the line 8—8, 60 Fig. 6;

Fig. 9, is a sectional view on the line 9—9, Fig. 6;

Fig. 10, is a perspective view of the cam for controlling the movement of the cutting 65 tool;

Fig. 11, is a detached perspective view of the tool holder;

Fig. 12, is an enlarged end view of a portion of one of the chucks showing the work 70 in section;

Fig. 13, is a sectional view on the line 13—13, Fig. 12;

Fig. 14, is a side view of means for adjusting the cam bar to control the movement 75 of the cutting tool;

Fig. 15, is a sectional view on the line 15—15, Fig. 14;

Fig. 16, is a view of the lever mechanism for positively retracting the tool; and 80

Fig. 17, is a view of one form of adjustable bearing for the boring bar.

I will first give a brief description of the machine.

On the bed plate, which is of any length 85 desired, according to the work to be bored, is mounted a head carrying the boring bar, which is of a greater length than any work to be finished on the machine. This head

has a longitudinal movement on the bed 90 sufficient to retract the boring bar clear of the work, which is held in the chucks. At the opposite end of the base is a rigid support for the overhanging end of the boring

bar so that when the tools are in action the 95 bar is held rigidly at both ends. The bar, in the present instance, has two guideways, one at each side, for the tool carriages, and a longitudinal screw at each side driven by mechanism in the head traverses the tool 100

carriers. Secured to each side of the boring bar is a cam plate, which is arranged to force the tools out against the pressure of springs so that as the tool carriage travels 105 over the cams the tool will be projected and retracted, according to the shape of the cams. Thus, an entire tubular structure for instance can be completely finished in any manner desired.

While the invention is adapted for boring 110

irregular internal shapes of all types, it is especially adapted for finishing the interior of torpedo casings and, therefore, the mechanism must be accurate. The chucks are adjustably mounted on the base and jaws are provided for rigidly holding the work. These jaws are power driven as it will be understood that the work rotates while the boring tool has a longitudinal movement in respect to the work.

Referring to the drawings, 1 is the base having guideways 2. 3 is a head mounted on the guideways of the base. On the base is a longitudinal rack 4 with which engages 5 a pinion 5 on a shaft 6 carried by the head and driven in any suitable manner from an electric motor 7. 8 is an operating lever, on moving which the carriage can be shifted longitudinally on the bed. 9 is the boring 10 bar of a greater length than the work to be bored and the outer end of this boring bar is reduced in the present instance, as shown in Figs. 1 and 2, and is adapted to a bearing 10 at the extreme end of the machine and can be held therein by a set screw 11 so that when the tools are working the boring bar is rigidly held at both ends, but when the boring bar is being adjusted to the work it overhangs the head 3 and is of 15 substantial cross section so as to rigidly carry its weight without deflection. The boring bar 9 is made in cross section, as illustrated in Figs. 4 and 5, and has two guideways 12—one at each side. These 20 guideways are undercut to receive the tool carriages 13. Extending longitudinally in each guideway is a feed screw 14 located as clearly shown in Fig. 5. One-half of the screw 25 engages the tool carriage so as to move it longitudinally. Each screw has a clutch 15 at the extreme end and arranged to be actuated by levers 16 to engage the driving heads 17 of the driving mechanism so that on operating the levers 16 either one 30 or both of the screws can be driven. I have not described the details of the mechanism within the head 3, as this may be modified without departing from the details of the invention.

By making the bar in the manner shown so that the tool carriages are located in recesses in the bar, I am enabled to make a bar of comparatively small cross section and yet of sufficient strength to withstand the 35 strains while the tools are cutting. I preferably make the bar cruciform in cross section, as shown, and locate the controlling cams at the base of the recesses, while the guides for each tool carriage are located at 40 the inner edge of the recesses, as shown.

The tool carriage 13 is made as clearly shown in Figs. 5, 6, 7, 8 and 9, and a plunger 18 is mounted in the carriage and has a concaved threaded recess at the inner end 45 to engage the feed screw 14. 19 is a hand

lever having a pin 20 arranged off center which enters the groove 21 in the plunger 18, and by moving the hand lever the plunger can be moved into and out of engagement with the feed screw. When it is desired to move the tool carriage by hand, a shaft 22 is provided having a head 23 to which a wrench can be applied and on the inner end of this shaft 22 is a pinion 24 which meshes with the threads of the screw 25 so that when the plunger 18 is withdrawn the carriage can be moved by hand, by turning the shaft.

25 is the tool post and 26 is the tool secured to the post in the ordinary manner by 30 screws 27. 28 is a spring connected at one end of the tool carriage and at its outer end to a lug on the tool post. The tendency of the spring is to draw the tool post in toward the center of the boring bar and away from 35 the work.

29 is a longitudinally arranged cam bar. This cam bar is secured in any suitable manner to the boring bar and is of a length equal to the travel of the carriage, as it will 40 be understood that in this type of machine there may be two or more carriages on each side of the boring bar, each carriage having a limited movement, although, in some instances, the cam bar may extend the full 45 length of the boring bar and a single carriage may be used. Adjustably carried by the tool post is a bearing block 30, which bears against the face of the cam bar and controls the movement of the tool post. 50 This bearing block can be adjusted by a screw 31 mounted in bearings in the tool post and this screw is provided with a head to receive the wrench. The screw, in the present instance, is made with two sets of 55 threads, one adapted to a thread in the post and the other in the bearing block so as to provide for minute adjustments.

In order to lock the screw in the position to which it is adjusted, I provide a clamp 60 pin 32 actuated by an adjusting screw 33, which actuates a block 34 having a tapered end. Thus it will be seen that the tool carriage is moved longitudinally in the guides of the boring bar and the movement of the 65 tool toward the work is controlled by the outside cam bar and the movement of the tool from the work is controlled by a spring.

In order to insure the proper moving of the cutting tool from the work so as not to 70 depend entirely upon the action of the spring, I provide a lever 62 which is attached to the block 30 by a pin 63, a cam 29^a on the cam bar 29 actuates the lever so that it will positively move the tool back 75 from the work, see Fig. 16. This is particularly adapted for use where the cut is heavy and where the side friction on the cutting tool might overcome the action of the spring.

By shaping the cam bar to conform with the finished interior of the material clamped to in the chucks, the tool will accurately bore the interior of the shell or other tubular structure to conform to the design of the cam bar.

The work to be bored is held in the present instance by two chucks mounted on the base 1 and illustrated in Figs. 4, 12 and 13. The 10 two chucks 35 are similar in construction, therefore, I will only describe one chuck. The chuck 35 has a base section 36 and a cap 37 secured thereto by bolts 38. The chuck is arranged to slide on the base 1 and has 15 plates 39 on each side extending under the flange of the base in the ordinary manner. The rack 4, which extends throughout the length of the base, is engaged in the present instance by a pinion 40 geared to a hand 20 operated shaft 41 so that on applying a handle to the end of the shaft 41 the chuck can be moved to any position desired. Mounted in the chuck is a carrier 42 to which is attached a worm wheel 43, which meshes with 25 a worm 44 on a transverse work shaft 45 adapted to bearings in the base section 36 of the chuck. On the outer end of this shaft is a bevel wheel 46, which meshes with a bevel wheel 47, shown in dotted lines in Fig. 4, 30 and splined to the shaft 48 driven through a train of gears 49, as shown by dotted lines in Fig. 1, from the shaft 50 of the motor 51, an electric motor in the present instance. The gears 46 and 47 are located within a box 35 36^a projecting from the base section 36 of the chuck, and this box also forms one of the bearings for the shaft 48 so that when the shaft 45 is turned the chuck carrier is 40 turned with it. Mounted on the carrier are three jaws 52, which are undercut at the back and adapted to undercut recesses in the carrier 42, as clearly shown in Fig. 4. Secured to the carrier are longitudinal rack bars 53 held to the carrier by screws 54, Fig. 45 13, and adapted to engage this rack bar is a worm wheel 55 on a shaft 56 carried by the jaws 52. The head 57 is formed on the end of the shaft 56 so that when a wrench is applied the shaft 56 and its worm wheel 55 can 50 be turned, and the jaws 52 can be drawn tightly onto the work α , in the present instance the tube of a torpedo, so as to lock the work firmly to the chuck.

As above remarked, both chucks are similar in construction and are turned in unison from the same shaft 48 as clearly shown in Fig. 1. Located between one edge of the undercut portion of each jaw 52 and the carrier is a gib 58, which can be taken up by 55 a set screw and nut 59 in the ordinary manner so that the parts of the chuck are rigid.

In some instances, it is necessary to cut right angled or steep shoulders on the work, and this I accomplish by disengaging the 60 tool from the feed screw 14 so that it will

remain stationary, and move the end cam bar longitudinally, so that it will travel past the tool carrier and feed the tool toward the work. In the present instance this is accomplished by means of a screw 64 adapted to a fixed bearing 65 engaging a nut 66 on the carrier, Figs. 14 and 15.

60 is a tool carrier arranged to slide on the base 1 and carrying an ordinary tool slide rest 61 holding a tool for finishing the 75 outside of the work when necessary. This outside cutter forms no part of my present invention.

While I have shown the mechanism driven by two electric motors, one mounted on the carriage 3 and the other located permanently at the side of the machine, the mechanism may be driven by other motors without departing from the essential features of the invention, and while I have illustrated my 80 invention as particularly adapted for boring the tubular casings of torpedoes, it will be understood that it can be used for boring the interior of any object which is of such a size as to accommodate a boring bar.

While I have illustrated a spring for holding the tool post against the cam, in some instances other equivalent means may be used without departing from the spirit of the invention.

In Fig. 2, of the drawings, the bearing 10 is shown as stationary, but in tools in which the length of the work varies considerably I may use an adjustable bearing 10^a arranged to slide on the base and may be shaped to 95 engage the body of the bar, as shown in Fig. 17.

The operation is as follows:—

The head is moved back by the pinion 5: meshing with the rack 4, drawing with it 105 the boring bar 9 until it is clear of the chucks and the work. The boring bar is of such a construction and the carriage is of such a design that the bar, although having an extended overhang, will be rigid. The 110 chucks are separated and the jaws are opened sufficiently to allow the work α to be placed in the chucks, after which they are adjusted and the jaws clamped tightly onto the work. When the head is moved forward, the boring bar enters the work and the end passes therethrough and is located in the bearing 10, so that the bar is firmly supported both at the inner and outer ends.

Prior to the insertion of the bar into the 115 work the particular cams are properly located on the boring bar and the tools are set in their respective positions. The motor 15 is then set in motion, turning the shaft 48, the two chucks, and the work α . The motor 120 7 is then started and the clutches 15 are shifted so that the screws 14 on the boring bar are turned and the tool carriages are traversed longitudinally on the bar, the tool post being projected or retracted according 125 130

to the particular shape of the cam bar. After the work has been finished, the head and the boring bar are moved longitudinally so that the boring bar will clear the work. 5 Then the clutches are shifted so as to release the work, which is removed from the machine and another shell is placed in position.

10 In Fig. 5, I have shown two longitudinal tubes arranged in the recesses of the boring bar. These tubes supply lubricant to the moving parts of the tool carriage. The details of the lubricating mechanism have been omitted from the drawings.

I claim:

15 1. The combination in a boring machine, of a base; a head mounted on the base; a boring bar carried by the head; a bearing for the outer end of the boring bar; chucks mounted on the base to which the work is secured; means for rotating the chucks; a tool carriage on the boring bar; a cam bar on the boring bar; a tool post mounted on the carriage; and means tending to hold the tool post against the cam so that the cam 20 will project the tool, the means retracting the tool.

25 2. The combination in a horizontal boring machine, of a base; a head slidably mounted on the base; a boring bar secured to the head; a fixed bearing at the opposite end of the machine on which the outer end of the boring bar is supported when in the working position; chucks mounted on the base and carrying the work through which the boring bar extends, the boring bar being recessed at each side; a tool carriage mounted in each recess; two longitudinal screws on the boring bar, one exposed in one recess and the other in the other recess; means on 30 each carriage for engaging its screw so as to feed the carriage longitudinally; means on the head for driving the screws; a longitudinal cam bar located in each recess; a tool post; means for holding the tool post 35 in engagement with the cam bar so that as the carriage is traversed by the screw the tool moves in conformity with the shape of the cam bar and makes a cut in the work corresponding to the contour of the cam bar.

40 50 3. The combination in a horizontal boring machine, of a base; a head; a boring bar projecting from the head, said boring bar having a longitudinal recess therein forming guides; a tool carriage mounted in the recess and arranged to travel on the guides; a longitudinal screw exposed in the recess; means for driving the screw carried by the head; means on the head for disengaging the carriage from the screw; hand means for 45 shifting the carriage on the boring bar; a tool post mounted on the tool carriage; a longitudinally arranged cam bar located in the recess; and yielding means for holding the tool post against the cam bar so that as 55 the tool carriage is traversed the tool post

and the tool carried thereby will be moved laterally by the cam bar.

4. The combination in a boring machine, of a boring bar recessed at one side; a longitudinal screw located in the recess; means for turning the screw; a longitudinally arranged cam bar also located in the recess; a tool carriage arranged to travel longitudinally in said recess; means on the carriage for engaging the screw; a tool post on the tool carriage; a bearing block adjustably mounted on the tool post and arranged to engage the cam bar; and yielding means for holding the tool post and its bearing block against the cam so that as the carriage is 80 traversed longitudinally by the boring bar on the screw the tool post and its tool will be moved laterally by the cam bar.

5. The combination in a boring machine, of a boring bar; longitudinal guides thereon; a tool carriage mounted on the guides; means for moving the tool carriage longitudinally; a cam bar mounted on the boring bar; a tool post mounted on the tool carriage; a spring tending to hold the tool post 90 against the cam bar so that as the carriage is moved longitudinally the tool will be projected or retracted as dictated by the cam bar.

6. The combination in a boring machine, 95 of a head; a boring bar carried thereby, said boring bar being recessed at each side and having longitudinal guides formed thereon; a tool carriage mounted at each side of the boring bar; two longitudinal screws, one 100 located on one side and the other on the opposite side of the boring bar, one screw being arranged to traverse one carriage and the other being arranged to traverse the other carriage; a longitudinal cam bar arranged at each side of the boring bar within the recess; a tool post on each carriage bearing against the cam bar; and means for 105 yieldingly holding the post against the bar, one carriage being out of line with the other 110 so that the two cutting tools are acting on work at different locations.

7. The combination in a boring machine, 115 of a base; a longitudinally movable head thereon; a boring bar carried by the head; two chucks mounted on the base; means for turning the chucks; a carrier mounted in each chuck; means for turning the carriers in unison; jaws mounted on each carrier for clamping the work, said jaws being tapered; 120 a rack bar for each jaw secured to the carrier; a shaft on each jaw having a worm wheel engaging the rack so that on turning the shaft the jaws will be moved to and from the work.

8. The combination in a horizontal boring machine, of a base; a head mounted to slide on said base; a boring bar carried by the head and overhanging the base; a fixed bearing at the opposite end of the machine to 130

- receive the end of the boring bar; means for securing the boring bar firmly in the bearing; two chucks mounted on the base; a carrier mounted in each chuck; jaws adjustably mounted in the carriers and arranged to clamp the work; a shaft at one side of the machine arranged to turn both carriers in unison; means for driving the shaft; a tool carriage on the bar; a tool post thereon; 10 means for moving the tool carriage longitudinally; and a cam on the bar for controlling the lateral movement of the tool post on the tool carriage.
9. The combination in a boring machine, of a boring bar; means for carrying said bar; a tool carriage mounted on the boring bar; means for traversing the tool carriage; a cam bar longitudinally arranged on the boring bar; a tool post laterally slidable on 15 the tool carriage; a boring block adjustably mounted on the tool post and arranged to bear against the cam bar; a spring having one end connected to the tool post and the other to the tool carriage; an adjusting screw; a clamp pin for engaging the adjusting screw; a screw; and a tapered block actuated by the screw for forcing the clamp pin against the adjusting screw to hold said adjusting screw in the position to which it is 20 adjusted so that as the carriage is traversed the tool post and its tool will be controlled laterally by the cam bar.
10. The combination in a horizontal boring machine, of a base; a head longitudinally movable on the base and carrying a long, overhanging boring bar; a motor mounted on the head; a longitudinal rack on the base; a pinion mounted on the head meshing with the rack and driven by the motor; two longitudinal screws extending on each side of the boring bar and also driven by said motor on the head; clutch mechanism for throwing the screws into engagement with the motor; a tool carriage mounted on each side of the 25 boring bar and traversed by the screws; a longitudinally arranged cam on each side of the boring bar, said cam being removably mounted on the boring bar; a tool post carried by the tool carriage; a spring tending to hold the tool post against its cam bar so that as the tool carriage is traversed the tool will be controlled by the cam bar; chucks mounted on the base for holding the work; and independent means for driving 30 the chucks.
11. The combination in a boring machine, of a boring bar cruciform in cross section forming longitudinal recesses at each side; guides in the recesses; tool carriages mounted on the guides; and means for traversing 35 said tool carriages.
12. The combination in a boring machine, of a boring bar recessed at each side; a tool carriage mounted in each recess, the major portion of the tool carriage being located in 40 the recess.
13. The combination in a boring machine, of a boring bar having a V-shaped groove in one side; guides within the groove; a tool carriage mounted in the guides; a cam bar 45 located in the base of the groove; a tool post mounted on the carriage and controlled by the cam; and means for feeding the carriage longitudinally.
14. The combination in a boring machine, of a boring bar having a deep V-shaped recess at each side; a longitudinal guide within each recess; a cam bar located at the base of each recess; a tool carriage mounted in each guide; and a tool post mounted in 50 each carriage and controlled by the cam bar.
15. The combination in a boring machine, of a boring bar; a tool carriage mounted on the bar; a cam bar carried by the boring bar; a feed screw; means detachably connecting the carriage with the feed screw; a tool post mounted on the carriage and controlled by the cam bar; and means for longitudinally moving the cam bar when the carriage is stationary to project the tool so 55 that it will cut an abrupt shoulder in the work.
16. The combination in a boring machine, of a boring bar having a deep longitudinal recess therein; a tool carriage mounted in 60 the recess; a tool post on the carriage; a cam bar at the base of the recess arranged to actuate the tool post; a feed screw; means on the carriage for engaging the feed screw so that when the carriage is disengaged 65 from the feed screw the cam bar will be moved longitudinally and will cause the tool post to move.
17. The combination in a boring machine, of a boring bar having a longitudinal recess 70 therein; a tool carriage mounted in the recess; means for feeding the carriage longitudinally on the boring bar; a tool post; a cam bar located in the recess and arranged to project the post; a spring for retracting 75 the tool post; and lever mechanism controlled by a cam on the cam bar for positively retracting the tool post.

ERNEST J. ROLLINGS.

It is hereby certified that Letters Patent No. 1,230,034, granted June 12, 1917, upon the application of Ernest J. Rollings, of Philadelphia, Pennsylvania, for an improvement in "Boring-Machines," were erroneously issued to the inventor, said Rollings, as owner of said invention, whereas said Letters Patent should have been issued to *Newton Machine Tool Works, Incorporated, of Philadelphia, Pennsylvania, a corporation of Pennsylvania, as assignee* of the entire interest in said invention, as shown by the records of this Office; and that the said Letters Patent should be read with this correction therein that the same may conform to the record of the case in the Patent Office.

Signed and sealed this 26th day of June, A. D., 1917.

[SEAL.]

R. F. WHITEHEAD,

Acting Commissioner of Patents.

Cl. 77—3.
